RADIO TELEGRAPH RECEPTION

Charles W. Earp, London, England, assignor to
International Standard Electric Corporation,
New York, N. Y., a corporation of Delaware

Application August 13, 1941, Serial No. 406,642
In Great Britain September 28, 1940

9 Claims. (Cl. 250—8)

The present invention relates to radio telegraph systems and receivers for use therein. One object of the invention is to guard against disturbance of the telegraph signals.

According to the invention, there is provided a radio telegraph system in which telegraph signals are radiated by intermittent interruption of a radio frequency wave modulated by a low frequency tone, the receiving apparatus being so arranged that it assumes the same predetermined condition when the transmission is disturbed, whether by interference or by fading.

Also according to the invention, there is provided a radio telegraph receiving arrangement for receiving telegraph signals which are radiated simultaneously on a plurality of different radio frequency waves, the receiving apparatus being so arranged that it assumes the same predetermined condition when the transmission is disturbed, whether by interference or by fading.

Embodiments of radio telegraph receiving arrangements according to the invention will now be described with reference to the accompanying drawings comprising Figs. 1-5.

Fig. 1 is a block schematic of a radio telegraph receiver according to the invention;

Fig. 2 is a circuit diagram of a thermionic valve circuit suitable for use as the unit CC in the arrangement of Fig. 1;

Figs. 3, 4 and 5 are modifications of Fig. 2.

The arrangement of Fig. 1 is a modification of the arrangement of Fig. 1 of my prior British patent specification No. 540,839, accepted Oct. 31, 1941, and the description given herein will therefore be restricted to a brief description of the prior arrangement and a more particular description of the changes which have been made therein. The prior arrangement was for receiving transmissions of the kind in which a telegraph channel is produced by the keying of a radio frequency wave which is then radiated from the antenna of a radio transmitter.

In order to provide greater freedom from the disturbance of the radio telegraph signals due to fading and due to interfering signals from other transmitters, it is now proposed to radiate the same signal simultaneously on a plurality of different radio frequency waves.

Transmission may conveniently be effected by intermittently interrupting a radio frequency wave which has been modulated by a low frequency tone; in this case the telegraph signals are radiated on three frequencies, viz. on a carrier and two sidebands. Another suitable transmission would be the keyed output from a bal-

anced modulator, when no carrier, but two equal sidebands would be radiated; this has the advantage that all the component waves have the same amplitude, so that similar receiving channels may be used for each wave. An analogous three frequency transmission may be effected by the keying of a partially balanced modulator, whereby three frequencies of equal amplitude may be produced.

The interrupted signals of all the frequencies are received on antenna AN₁ of the receiver of Fig. 1. These signals are amplified in an amplifier A₁ the output of which is passed through a frequency changer comprising a detector D₁ and oscillator O₁. The resultant intermediate frequencies are then amplified in A₂. The output of A₂ is applied to a second detector D₂ where the frequencies are again reduced by action of oscillator O₂ to values which may be more easily separated by selector filters F, F' and F'' to apply the signals of different signal frequencies to separate signal paths SP, SP', SP'', the outputs of these paths being applied to a conversion circuit CC to be described in more detail later. The output of CC is applied to the telegraph relay circuit RC which repeats the marking and spacing telegraph impulses. The signals are applied over security apparatus SA, which serves to repeat the signals back to the transmitter, to teleprinter recorder TP.

A second output of detector D₂ is connected over band pass filter F₁, which will pass all the signal frequencies, as well as interference voltages, and amplifier A₃ to detector D₃. The output of D₃ is applied over interference path IP to a second input of converter CC, a low pass filter F₂ being used if required.

The most obvious method of applying these outputs to the circuit CC would be to combine them and to apply the combined output to the input of a simple valve circuit. This method, however, would have the serious disadvantage that the interference components in all the signal paths would add up to produce a voltage which would be much greater than when receiving on a single frequency. The interference filter F₂ would consequently have to be increased in band width, or alternatively the noise level in this filter would have to be raised by increasing the gain of the amplifier A₃. This would result in the disturbing effect of interference being seriously increased, for during selective fading affecting only one of the received signals the combined signal strength would be reduced whereas the in-

terference voltage applied over the interference path IP would remain substantially unchanged.

Fig. 2 shows a modified arrangement of the conversion circuit CC which overcomes this difficulty by arranging that the signal paths SP, SP', SP'' operate into individual rectifiers RS, RS', RS'' which operate into a common load circuit.

Using the circuit of Fig. 2, the rectified voltage delivered to the grid of valve V3 corresponds to the strongest of the three received signals. If the output on SP is the strongest signal, for example, the grid of V3 becomes biased negatively by the operation of rectifier RS. The rectified voltage set up across the grid resistance R7 automatically biases the rectifiers RS' and RS'' so that the smaller outputs on SP' and SP'' are not operative. If only interference is present on the channels SP, SP', SP'', then the peak rectified voltage applied to V3 over interference path IP is substantially the same as the peak rectified voltage that would be applied thereto due to the interference on a single channel. Thus, since R8 carries large rectified current, tube V4 is biased to cut-off and no marking signals are repeated into RC. This arrangement also avoids the disadvantage that if the different frequencies were added together before rectification, signal envelopes would be produced at the difference frequencies.

Fig. 3 is a modification of Fig. 2, dispensing with the valve V3. In this case the rectifiers RS, RS', RS'' are connected in the opposite sense to their connections in Fig. 3 so their outputs tend to drive the grid of V4 positively. The output from R1 tends to drive the grid of V4 negatively so that the voltage actually applied to the grid of V4 is the difference between the voltages set up across R7 and R8.

Fig. 4 is a modified circuit designed to give a high freedom from interfering signals. Each signal path SP, SP', SP'' has its own rectifier RS, RS', RS'', and each rectifier its own load resistor R7, R'7, R''7, and each load has, associated with it, a separate valve V3, V3', V3''. In order that a mark signal can be sent to the relay circuit RC, signals must be present on all the signal paths, so that all the valves V3, V3', V3'' are driven to cut-off. If there is no signal on any one of the signal paths, then the associated valve will draw anode current and bias the valve V4, thus preventing the relay circuit RC taking up the mark condition. It will be seen, therefore, that a false mark cannot be produced by interference unless it is present on all signal paths, and absent from the interference path.

Fig. 5 shows a further modification in which a separate interference path is provided for each signal path. The separate interference paths IP, IP', IP'' are connected through separate rectifiers RI, RI', RI'' to a common load circuit C3, R8 which thus receives a voltage proportional to the maximum interference on any of the channels IP, IP', IP''. This provides protection against false marking by interference which happens to be present on all signal paths at once, for interference which is present on all signal paths is highly likely to be present on at least one interference path. If so, then a false mark is prevented. It should be noted that the use of several interference paths does not affect the overall signal-to-noise ratio for normal types of noise which are uniformly distributed throughout the frequency bands used.

I claim:

1. A radio telegraph receiving arrangement

comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said last named means comprising telegraph relay apparatus arranged to assume a marking condition in response to a marking signal being received over any one of said radio frequency waves.

2. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said last named means comprising telegraph relay apparatus arranged to assume a marking condition only when a marking signal is received over all of said radio frequency waves in the absence of any substantial interference.

3. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, and separate signal paths coupled to said signal filters, said control means including a further filter to select interference waves and apply them to an interference path.

4. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising signal filters to select signal currents corresponding to said different frequency waves, separate signal paths coupled to said signal filters, a further filter to select interference waves and apply them to an interference path, and individual rectifiers which have their output circuits connected in parallel coupled to the outputs of said signal filters.

5. A radio telegraph receiving arrangement comprising means for simultaneously receiving signals radiated simultaneously on a plurality of different radio frequencies, a receiver amplifier, selective means selectively applying signals representative of said different radio frequencies to

said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, separate signal paths coupled to said signal filters, a further filter to select interference waves and apply them to an interference path, and a resistance capacity circuit connected to automatically bias all of said rectifiers to an extent which is proportional to the greatest of the outputs applied to said rectifiers.

6. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, separate signal paths coupled to said signal filters, a further filter to select interference waves and apply them to an interference path, and individual rectifiers which have their output circuits connected in parallel coupled to the outputs of said signal filters, and an individual rectifier in the output of said further filter which has its output circuit so connected that the voltage produced therein has an opposing effect to that produced by that of the signal rectifiers.

7. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, separate signal paths coupled to said signal filters, a further filter to select interference waves and apply

them to an interference path, and individual rectifiers which have their output circuits connected in parallel coupled to the outputs of said signal filters, and an individual rectifier in the output of said further filter, said rectifiers all being connected in the same sense, a first valve, a second valve, the output from the interference rectifier being applied directly to the grid of said second valve whilst the output from the signal rectifiers is applied to the grid of said second valve via said first valve.

8. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, separate signal paths coupled to said signal filters, a further filter to select interference waves and apply them to an interference path, and individual rectifiers which have their output circuits connected in parallel coupled to the outputs of said signal filters, and an individual rectifier in the output of said further filter, a valve, the outputs from all of said rectifiers being applied to the grid of said valve, the interference rectifier being connected in the opposite sense to the signal rectifiers.

9. A radio telegraph receiving arrangement comprising means for simultaneously receiving signals radiated simultaneously on a plurality of different radio frequencies, a receiver amplifier, selective means selectively applying signals representative of said different radio frequencies to said receiver amplifier, and control means in said receiver responsive to either interference disturbances or fading of said signals to cause said receiver amplifier to assume a common predetermined condition indicative of the interference, said selective means comprising separate signal filters to select signal currents corresponding to said different frequency waves, separate signal paths connected to said signal filters, and a like number of separate interference filters to select interference currents and apply said selected interference currents to separate interference paths.
